UNITED STATES PATENT OFFICE.

WILLIAM G. HARTWIG, OF CHICAGO, ILLINOIS, ASSIGNOR TO ARTHUR FRANTZEN, OF CHICAGO, ILLINOIS.

THERMO-ELECTRIC REGULATOR.

1,300,215.

Specification of Letters Patent.

Patented Apr. 8, 1919.

Application filed July 16, 1917. Serial No. 180,780.

To all whom it may concern:

Be it known that I, WILLIAM G. HARTWIG, a citizen of the United States of America, and resident of Chicago, Cook county, Illinois, have invented a certain new and useful Improvement in Thermo-Electric Regulators, of which the following is a specification.

This invention relates to thermo-electric regulators in general, but more particularly to those for controlling the electric heating apparatus on street cars, and especially those in which the electro-magnetically-operated switch-mechanism is controlled by a thermostatic to automatically open and close the circuit of the heating apparatus.

Generally stated, the object of this invention is to provide a novel and improved thermo-electric regulator of the foregoing general character.

A special object is to provide a novel construction and arrangement whereby less current will be consumed by the regulator in the general operation thereof.

It is also an object to provide certain details and features of construction tending to increase the general efficiency and desirability of a thermo-electric regulator of this particular character.

To the foregoing and other useful ends, this invention consists in matters herein-after set forth and claimed.

In the accompanying drawings, the single figure is a diagram of a thermo-electric regulator embodying the principles of the invention.

As thus illustrated, this invention comprises a line A, over which suitable current is supplied, such as that of the ordinary street car trolley line, which for ordinary purposes is a direct current. On the street car, the resistance B is suitably connected with the trolley which engages the line, and this resistance is connected with one terminal of the coil of the relay C, and also with the movable contact element 1 of said relay. It will be seen that this element 1 is L-shaped, and that one arm thereof is adapted to be raised by the armature 2, when the latter is attracted by the core of the relay, and that the other arm of the element 1 is adapted to engage the stationary contact 3, where the contacts 1 and 3 are separated when the armature is attracted. The element 1 is of metal, and the armature 2 engages this

element to close another circuit, as will hereinafter more fully appear. The thermometer thermostat D has one terminal thereof connected with the other terminal of the coil of the relay C, and the other terminal of the thermostat is connected with one terminal of the auxiliary operating coil E, which latter is a part of the main electro-magnetically-operated switch-mechanism. The other terminal of the operating coil E is connected with the armature 2, so that when this armature engages the element 1, current is supplied from the resistance B through the contacts 1 and 2 and the coil E to ground at 4, thus energizing said coil. The main operating coil F has one terminal thereof connected to ground, and has its other terminal connected to the movable switch contact 5, which latter swings up and down and has a spring 6 by which it is raised into normal position. The pivoted latching device 7 has a notch 8 to receive the end of the armature 9, which latter is disposed below the lower end of the core of the operating coil F, and the other end of this device 7 is provided with a body of insulation 10 for engaging the contact 5, thereby to press the latter downward into engagement with the stationary contact 11 when the operating coil E is energized. The armature 9 has an arm 12 which engages the stationary contact 13 when the armature is in its attracted position. This contact 13 is connected with the heaters G, which latter may be of any suitable character, and the other terminal of the heaters is connected with the trolley which engages the line or current main, so that said heaters are in operation when their circuit is closed at the contacts 12 and 13, this heating circuit being through the heaters 90 and said contacts and then to ground at 4, whereby a street car is heated in the desired manner.

With the foregoing arrangement, the mode of operation is as follows: With the parts 100 in the position shown, the circuit of the heaters G is closed. When the temperature rises above the desired point, the thermostat closes the circuit from the resistance B over the conductor 14 to the coil C, from the latter over the conductor 15 to the thermostat, through the thermostat and over the conductor 16 to the ground at 4, whereby the relay C is energized. This attracts the armature 2, causing the element 1 to disengage 110

the contact 3, and at the same time closing a circuit from the resistance B over the conductor 17 to the element 1, through the armature 2 and over the conductor 18 to the 5 operating coil E, and from the latter to ground. The energizing of the operating coil E, by the closure of the contacts 1 and 2, causes the core of this coil to attract the device 7, which latter is constructed to act as 10 an armature, thereby causing the insulation 10 to press the contact 5 into engagement with the contact 11, and causing the armature 9 to be disengaged from the notch 8, whereby this armature 9 drops downward. 15 This disengages the contact 12 from the contact 13, and the result is that the circuit of the heaters G is opened. During this time, of course, the coils C and E are connected in multiple, and are in parallel with each 20 other, and hence current passes through the coil E to reduce the current flow in the thermostat D, so that the latter always closes on relatively high potential and opens on relatively low potential, the current being 25 reduced in the thermostat immediately after the operation thereof. It will also be seen that before the operating coil E was energized, and while the heaters G were receiving current, the circuit of the operating coil F 30 was open, the contacts 5 and 11 being separated at that time, so that while the heaters G are in operation there is no current flowing through the operating coil F, which reduces the maximum or peak load and causes 35 the apparatus to consume less current in the general operation thereof. When the temperature falls, the thermostat D opens the circuit of the relay C, causing the latter to release the armature 2 from the contact ele- 40 ment 1, thereby opening the circuit of the operating coil E, but this does not result in separating the contacts 5 and 11, for at this time the armature 9 is down and is holding the device 7 in position to keep said contacts 45 closed. Consequently, when the relay C is deenergized, allowing the element 1 to engage the contact 3, a circuit is then closed from the resistance B over the conductor 17 to the contacts 1 and 3, over the conductor 50 19 to the contact 11, through the contact 5 and over the conductor 20 to the operating coil F, then over a short conductor 21 to the arm 12, and then over the conductor 22 to ground at 4, thus energizing the coil F and 55 causing the armature 9 to move upward. While the armature 9 is moving, the contacts 5 and 11 are held together, but these contacts separate as soon as the armature snaps into the notch 8, as this permits the spring 6 to 60 lift the contact 5 and to thereby tilt the device 7 into locking position, so that the armature 9 is held in its raised position. This closes the contacts 12 and 13 and the heaters G can receive current for heating purposes. 65 Thus, it will be seen that the electro-mag-

netically-operated switch-mechanism comprises two operating coils E and F, but that no current flows through the coil F while the heaters G are receiving current for heating purposes. The other operating coil E 70 receives current while the heaters G are out of use—that is to say, while the heating circuit is open, but the current thus allowed to pass through the coil E is for a useful purpose, inasmuch as this very materially reduces the flow of current in the thermostat D, but without reducing the current in the relay C to the extent that the latter will be liable to release its armature. Hence, the thermostat D will then open its circuit under 75 favorable conditions, the potential having been reduced to an extent to prevent sparking in the thermostat, which would not be desirable and which might be injurious in a thermometer thermostat. The locking device 80 85 85 retains the armature 9 in attracted position, and the operating coil E is energized to operate this device and thereby release said armature when the thermostat D operates in response to a rising temperature 90 to open the heating circuit. The operating coil F only momentarily receives current, each time the contacts 1 and 3 close, for the current flow in this coil is automatically discontinued practically immediately by the 95 separation of the contacts 5 and 11, in the manner previously explained.

As shown, the coil C is of about 1200 ohms resistance, the coil E of about 50 ohms, and the coil F about 850 ohms, but this may be 100 changed or varied to suit the requirements. Also, of course, the armatures 2 and 9 are pivoted in such manner that they have only limited downward movement, thereby to insure the desired mode of operation. The 105 theremo-electric regulator thus provided, which includes the two magnets and the relay and the thermostat and their circuits, is entirely free from current flow when the heating circuit is closed, so that the peak 110 load, as stated, is materially reduced in any street car or other system in which larger numbers, or any number, of heaters are employed. For when the heaters are receiving current there is no current in the regulator. 115 Should the trolley be disengaged from the line, while the heaters are receiving current, the apparatus will not be distributed, and the current will continue to be supplied to the heaters as soon as the trolley is restored 120 to the line. Also, should the trolley leave the line while the heating circuit is open, no current will be supplied to the heaters when the trolley is restored to the line. The 125 resistance of the coil B may be of any suitable character, depending on the voltage of the line circuit.

From the foregoing, it will be seen that the main switch or contactor by which the heating circuit is controlled is not main- 130

- tained in closed position by the energizing of any operating coil. To the contrary, this switch is kept closed by the locking device, so that the use of any operating coil as a retaining coil, or the use of a separate retaining coil, is not necessary, as the locking arrangement obviates the necessity of using either of these things. Again, the circuit arrangement, it will be seen, retains the advantage of having the contactor or main switch included in the connection between the heater and the ground, instead of in the connection from the heater to the source of current, as well as the other feature of reducing the current in the thermostat before the regulator is operated by falling temperature. The two operating coils and the relay coil, it will be seen, are connected in separate multiple series, so that they are in parallel with each other, and with the heater, and none of these coils are ever in series with each other, because each coil has practically a separate circuit which does not include any other coil. Thus, the contactor or main switch has a plurality of operating coils, but means are provided to maintain the contactor or main switch in closed position, so that there is no current flowing in the circuit of any operating coil while the heater circuit is closed, and no operating coil is employed as a retaining coil to maintain the switch or contactor closed. Also, with the arrangement shown and described, it is possible, it will be seen, to use alternating current.
- 35 What I claim as my invention is:—
1. A thermo-electric regulator comprising a thermostat, a circuit including said thermostat and controlled thereby, means to supply electric current to said circuit, automatic devices to reduce the current in said thermostat after closure and before the opening of said circuit, so that the current is high when the thermostat closes and low when it opens, a heater, a circuit for said heater, a switch having mechanism operated by the energizing of said coil to open the heater-circuit, said devices including a coil for operating said switch.
  2. A thermo-electric regulator as set forth in claim 1 in which there is an auxiliary coil for controlling said mechanism to close the heater-circuit when the thermostat-circuit is closed.
  3. A thermo-electric regulator as set forth in claim 2 in which said mechanism has means to automatically deenergize the auxiliary coil upon the closing of the heater-circuit.
  4. A thermo-electric regulator comprising a thermostat, a circuit including said thermostat and controlled thereby, means to supply electric current to said circuit, automatic devices to reduce the current in said thermostat after closure and before the opening of said circuit, so that the current is high
- when the thermostat closes and low when it opens, a heater, a circuit for said heater, a switch for controlling said heater-circuit having mechanism provided with means whereby the entire regulator is free from the current flow while the heater-circuit is closed, said devices including a coil for operating said switch.
5. A thermo-electric regulator, comprising a thermostat, a circuit including said thermostat and controlled thereby, means to supply electric current to said circuit, automatic devices to reduce the current in said thermostat after closure and before the opening of said circuit, so that the current is high when the thermostat closes and low when it opens, a heater, a circuit for said heater, a switch for controlling said heater-circuit having mechanism to lock the heater-circuit closed, and a second coil to actuate said switch into closed position, said devices including a coil for operating said switch.
6. A thermo-electric regulator-system, comprising a heating circuit, a switch to open and close said circuit, a main coil to close said switch, an auxiliary coil to open said switch, means including a thermostat to control the flow of current in said auxiliary coil so that said switch is opened by a rising temperature and devices operated by the auxiliary coil to control the energizing circuit of the main coil, said means also including a relay which controls said circuit of the main coil, so that said relay and auxiliary coil jointly control said energizing circuit.
7. A thermo-electric regulator system comprising a heating circuit, a switch to open and close said circuit, a main coil to close said switch, an auxiliary coil to open said switch, means including a thermostat and a relay to control the flow of current in said auxiliary coil, said main coil having its energizing circuit controlled by said relay whereby the main coil is energized by the energizing of the relay.
8. The combination, in a thermostatically-controlled electric heating system, of a heater having a circuit for supplying current thereto, a switch for opening and closing said circuit, mechanism having a plurality of operating coils to control said switch, circuit for said coils, said mechanism having devices to maintain said switch closed, so that no operating coil is energized while current is flowing in the heater, and means to thermostatically control one of said circuits, whereby said operating coils jointly control said switch to automatically open and close the heater circuit.
9. A thermostatically controlled heating system comprising a heater, means for thermostatically controlling the production of heat thereby comprising a main coil, an armature therefor controlling the heater, a

catch for maintaining the armature in attracted position independently of said main coil, an auxiliary coil operating when energized to withdraw the catch to permit the 5 arm to drop, a pair of contacts in circuit with the main coil and closed by the auxiliary coil when the latter is energized, a relay operating when energized to open the main coil circuit and close the auxiliary coil 10 circuit, and a thermostat in circuit with the coil of the relay.

10. In a thermostatically controlled heating system, a switch controlling the heating circuit, a main coil for closing the switch, 15 means for holding the switch closed, an auxiliary coil for releasing the switch from said means, a relay, a thermostat in circuit with the coil of said relay, the thermostat and relay coil being in parallel with the auxiliary coil, the relay controlling the circuits of both the auxiliary and main coils closing 20

the former and opening the latter when operated.

11. The said system, as specified in claim 8, having means controlled by one coil to 25 momentarily close the circuit of another coil when the thermostat is operated by falling temperature.

12. The said system, as specified in claim 8, having means to momentarily close the 30 circuit of one magnet to close said switch when the thermostat is operated by falling temperature.

13. The said system, as specified in claim 8, and means controlled by one of said coils 35 to reduce the current in said thermostat before the regulator is operated by falling temperature.

Signed by me at Chicago, Illinois, this 14th day of July, 1917.

WILLIAM G. HARV WIG.
